UNITED STATES PATENT OFFICE.

JOHN G. PETTIS, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

REGULATING-VALVE.

1,184,012.

Specification of Letters Patent. Patented May 23, 1916.

Application filed August 7, 1914. Serial No. 855,642.

To all whom it may concern:

Be it known that I, JOHN G. PETTIS, residing at Chicago, in the county of Cook and State of Illinois, have invented new and 5 useful Improvements in Regulating-Valves, of which the following is a full, clear, and exact description.

My invention relates to valves for regulating the pressure of gas or liquid flowing 10 therethrough.

The object of my invention is to provide a diaphragm actuated regulating valve in which the expansion of the diaphragm is assisted by other expanding devices independently of the pressure of the gas or liquid to regulate and decrease the flow thereof into the expansion chamber. This I accomplish 15 by the comparatively simple means herein-after fully described, and as particularly 20 pointed out in the claims.

In the drawings: Figure 1 is a vertical central section of my improved valve. Fig. 2 is a similar view taken on dotted line 2—2, Fig. 1. Fig. 3 is a plan view of a bushing used in connection with my improvements. Fig. 4 is a similar view of the valve-plate in 25 connection therewith.

The housing of my improved valve comprises a central section A; an upper section 30 B, and a lower section C.

The lower section consists of a bell-shaped member the upper annular edge *a* of which is flanged vertically and is interiorly screw-threaded. The central portion of its bottom 35 has a cylindrical tube or well *b* depending axially therefrom, and the lower end of this tube *b* is contracted and provided with a screw-threaded opening which is engaged by the axially extending gage-screw *c*. Between the annular edge *a* and the mouth of 40 the bore of tube *b*, the bottom of lower section C is inclined downward to provide space for the accommodation of the dia- phragm and its connections, as clearly shown 45 in the drawings.

The central section A of the casing consists of an exteriorly screw-threaded cylindrical lower zone *d* which screws into the 50 annular flanged edge *a* of the lower section of the casing, and above this zone its sides taper inward to its upper edge which is interiorly threaded, as shown. The lower edge of the central section is built inward a suitable distance and is provided with an 55 annular groove in its underside that forms

a downwardly extending inner circular bead or rim *e* over which the margins of the diaphragm D extend. These margins are bent or flanged upward over the annular edge of rim *e* and enter the hereinbefore mentioned 60 annular groove and are confined and secured therein so as to hold the web of the diaphragm tight across the opening bounded by said rim, by a suitable solder E, or in any other manner.

The lower face of the diaphragm has a circular arbor F secured concentrically thereto, and this arbor has an integral tubular stud *f* projecting axially downward therefrom which centers the upper end of a comparatively stiff coiled expansion spring G. The lower end of this spring is seated on the circumferential flange of a centering-head *g*, and the pointed end of the gage-screw *c*, hereinbefore referred to, engages a central 75 recess in the underside of the latter.

The upper face of the diaphragm is engaged by a head H, which is, preferably, circular, and it has an integral screw-threaded stud projecting downward through a central opening in the diaphragm, onto which the central boss of the arbor F is tightly screwed so as to clamp the diaphragm between them. This head has two plungers *h*, 80 *h*, projecting upward therefrom diametrically opposite each other that pass vertically through suitable guide-openings in a bridge or cross-bar I, which latter is made integral with and connects the tapering sides of the central section of the casing above the plane 90 of its lower zone. The upper ends of the said pistons are reduced in diameter and these reduced portions extend through suitable openings in a circular-plate J, which latter is secured thereon by nuts *j*, *j*, concentrically to the axis of the casing, substantially as shown in the drawings.

Plate J is provided with a central tubular boss *k* that projects upward, and has a series of perforations therein encircling said boss 100 to permit the free circulation of the gaseous or liquid medium within the casing. A screw-threaded plug K is screwed downward through boss *k*, and the lower extremity of this plug is recessed and has seated therein a pad *m* of rubber or other suitable material, which engages the apex of the tapered nozzle M, and regulates the flow of gas or liquid discharged from the orifice thereof. The lower end of this nozzle is re- 110

duced and screw-threaded and tapped into the upper side of the bridge I in axial alinement with the center of the diaphragm and the axis of the plug, and its bore communicates with the horizontal intake passage N extending longitudinally into said bridge and constitutes a continuation of the bore of an outside tubular stub O projecting laterally from the central section of the casing 10 in alinement with said bridge, which latter is connected at its outer end with the source of gaseous or fluid pressure, and has a lateral branch for the accommodation of a pressure-gage (not shown) if desired. The 15 said central section of the casing also has a lateral stub Q projecting therefrom, preferably, at right angles to stub O, out through which the gas or liquid, whose pressure has been regulated by my valve, is discharged. 20 I prefer to insert a cylindrical bushing R into the upper end of the central section of the casing. This bushing has a circumferential flange r projecting from it near its lower edge, the periphery of which is threaded and adapted to engage the female threads in the upper end of said central section, and said flange r has a series of perforations r' therethrough to permit of the free circulation 25 of the gas or liquid. This bushing 30 serves to guide the vibrations of the plate J, the outer circumference of which latter engages the bore of the bushing.

The upper section B of the casing is of an inverted cup-shape, and it has a circumferential flange s near its lower annular edge, between which and said edge it is exteriorly screw-threaded and is adapted to screw into the upper end of the central section of the casing and surrounds the upper 40 portion of bushing R, substantially as shown in the drawings. The upper end of section B terminates, preferably, in a suitable axially extending stub T, which may be closed in any suitable manner, or may connect with a suitable pressure gage (not 45 shown), if desired.

In order to keep the discharge orifice of the nozzle normally closed, particularly when my improved valve is not in use, I 50 prefer to surround the plunger between head H and the bridge I with coil expansion springs x, x. The construction and normal position of the diaphragm may be depended upon to accomplish such closure, however, 55 and in such event, said springs x, x, may be dispensed with. The springs x, x, not only serve to supplement the action of the diaphragm, but they also tend to maintain the bridge I, separated from said diaphragm 60 with a yielding force when employed, and thus facilitate the operation.

What I claim as new is:—

1. A regulating valve comprising a casing having an upper bell-shaped section, an intermediate section and a lower section, a

horizontal bridge extending diametrically and completely across the intermediate section said bridge being fairly wide and having a longitudinal bore, a discharge passage extending perpendicularly from the inner extremity of said longitudinal bore, and two vertical openings located on opposite sides of the discharge passage and in transverse alinement therewith, a diaphragm secured to the outer lower edge of the intermediate section, a pair of plungers projecting vertically upward from the diaphragm and parallel to the axis of the casing, said plungers being closer together than the width of the bridge and slidably extending through the vertical side openings in the bridge, a plate connected to the upper extremities of the plungers, a closure device for the discharge passage in the bridge mounted in said plate, said plate being adapted to slide vertically in the upper section, a tubular sleeve depending from the lower section, and diaphragm controlling springs located in said tubular sleeve.

2. A regulating valve comprising a casing having an upper bell-shaped section, an intermediate section and a lower section, a horizontal bridge extending diametrically and completely across the intermediate section said bridge being fairly wide and having a longitudinal bore, a discharge passage extending perpendicularly from the inner extremity of said longitudinal bore, and two vertical openings located on opposite sides of the discharge passage and in transverse alinement therewith, a diaphragm secured to the outer lower edge of the intermediate section, a pair of plungers projecting vertically upward from the diaphragm and parallel to the axis of the casing, said plungers being closer together than the width of the bridge and slidably extending through the vertical side openings in the bridge, a plate connected to the upper extremities of the plungers, a closure device for the discharge passage in the bridge mounted in said plate, said plate being adapted to slide vertically in the upper section, a tubular sleeve depending from the lower section, and diaphragm controlling springs located in said tubular sleeve.

3. A regulating valve comprising a casing having an upper bell-shaped section, an intermediate section and a lower section, a horizontal bridge extending diametrically and completely across the intermediate section said bridge being fairly wide and having a longitudinal bore, a discharge passage extending perpendicularly from the inner extremity of said longitudinal bore, and two vertical openings located on opposite sides of the discharge passage, and in transverse alinement therewith, a dia-

- phragm secured to the outer lower edge of the intermediate section, a pair of plungers projecting vertically upward from the diaphragm and parallel to the axis of the casing; said plungers being closer together than the width of the bridge and slidably extending through the vertical side openings in the bridge, a plate connected to the upper extremities of the plungers, and a plug arranged in said plate and adapted to form a closure device for the discharge passage in the plate; said plate being slidably arranged in the upper section of the casing.
- 5 4. A regulating valve comprising a casing having an upper bell-shaped section, an intermediate section and a lower section, a horizontal bridge extending diametrically and completely across the intermediate section said bridge being fairly wide and having a longitudinal bore, a discharge passage extending perpendicularly from the inner extremity of said longitudinal bore, and two vertical openings located on opposite sides 20 of the discharge passage and in transverse alinement therewith, a diaphragm secured to the outer lower edge of the intermediate section, a pair of plungers projecting vertically upward from the diaphragm and 25 parallel to the axis of the casing; said plungers being closer together than the width of the bridge and slidably extending through the vertical side openings in the bridge, a plate connected to the upper extremities of the plungers, a screw plug centrally arranged in said plate and vertically adjustable therein, and suitable closure material in the lower end of said plug adapted 30 to engage and close the outlet of the discharge opening; said plate being slidably arranged in the upper section of the casing.
- 35 5. A regulating valve comprising a casing having an upper bell-shaped section, an intermediate section and a lower section, a horizontal bridge extending diametrically and completely across the intermediate section said bridge being fairly wide and having a longitudinal bore, a discharge passage 40 extending perpendicularly from the inner extremity of said longitudinal bore, and two vertical openings located on opposite sides of the discharge passage and in transverse alinement therewith, a diaphragm secured to the outer lower edge of the intermediate section, a pair of plungers projecting vertically from the diaphragm and parallel to the axis of the casing, said plungers being closer together than the width of the 45 bridge and slidably extending through the vertical side opening in the bridge, a plate connected to the upper extremities of the plungers, and a plug arranged in said plate and adapted to form a closure device for the discharge passage in the plate; said plate being slidably arranged in the upper section of the casing in which the plate is slidably mounted.
- 50 6. A regulating valve comprising a casing having an upper bell-shaped section, an intermediate section and a lower section, a horizontal bridge extending diametrically and completely across the intermediate section said bridge being fairly wide and having a longitudinal bore, a discharge passage extending perpendicularly from the inner extremity of said longitudinal bore, and two vertical openings located on opposite sides of the discharge passage and in transverse alinement therewith, a diaphragm secured to the outer lower edge of the intermediate section, a pair of plungers projecting vertically upward from the diaphragm and parallel to the axis of the casing, said plungers being closer together than the width of the bridge and slidably extending through the vertical side openings in the bridge, a plate connected to the upper extremities of the plungers, a screw plug centrally arranged in said plate and vertically adjustable therein, and suitable closure material in the lower end of said plug adapted to engage and close the outlet of the discharge opening, and a bushing fitting in the upper section of the casing in which the plate is slidably mounted.
- 55 7. A regulating valve comprising a suitable casing, a transverse diaphragm dividing the interior thereof into two chambers, a bridge connecting the sides of said casing of one of said chambers and having a longitudinal bore therein and an outlet nozzle extending perpendicularly from said bore, a suitable outlet pipe leading from said chamber in which said bridge is located, a pair of plungers arranged diametrically opposite each other and extending parallel to the axis of the casing from the diaphragm through said bridge, a plate connecting the ends of said plungers opposite said diaphragm, a screw-threaded plug tapped axially into said plate, suitable closure material inserted in the end thereof which is adapted to engage the outlet of said nozzle and regulate the discharge therefrom, and a suitable bushing within which said plate moves.
- In witness whereof I have hereunto set my hand this 30th day of July, 1914.
